UNITED STATES PATENT OFFICE.

EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

WRITING-MACHINE.

No. 858,284.

Specification of Letters Patent.

Patented June 25, 1907.

Application filed November 9, 1905. Serial No. 286,486.

To all whom it may concern:

Be it known that I, EDWARD B. HESS, a citizen of the United States, residing in the borough of Brooklyn, city of New York, State of New York, have invented certain new and useful Improvements in Writing-Machines, of which the following is a specification.

This invention relates to marginal stop and tabulator devices of a typewriting machine having a transversely traveling platen. It comprises certain improvements in operating mechanism hereinafter set forth in detail.

In the accompanying drawings: Figure 1 is a view in longitudinal vertical section taken adjacent the left hand side of the machine; Fig. 2, a similar section taken adjacent the right hand side of the machine. Fig. 3, a rear elevation; Fig. 4, a detail plan view showing a controlling rock shaft and associated parts for governing the position of the frame stop that co-operates with the margin and tabulator stops on the carriage; and Fig. 5, a longitudinal vertical sectional view taken adjacent the left hand side of the machine showing a modification or addition.

a is the platen suitably mounted in a carriage, of which *b*, *b*, are the end plates appropriately connected by cross bars one of which *c* is shown. At the front, the carriage runs upon a ball bearing *d*, and, at the rear, the bar *c* runs upon a roller *c'* mounted on a bracket *c''* fast to the main frame. Adjacent the rear of the carriage is a toothed margin stop bar *e* upon which are removably mounted margin stops *e'*; there being one for the right hand margin and one for the left. In rear of this toothed bar is a toothed tabulator stop bar *f* upon which are removably or adjustably mounted any desired number of tabulator stops *f'*—preferably, flat and relatively thin, as seen in Fig. 3. Between the bars *e*, *f*, is a vertically disposed lever *g* pivoted at *h* in a bracket *h'* upon an axis parallel with the axis of the platen. The lever *g* extends downwardly from its pivot inside the rear plate of the frame, its lower vertically disposed end *g'* being opposite and in front of the upper end *i* of an upwardly extending arm *i'* fixed to a transversely disposed rock shaft *k* turning in bearings in the side plates of the frame. The arm *i'* has also adjacent its upper end a lateral projection *i''* adjacent

and in front of which stands the downwardly extending end *m* of a lever pivoted at *m'* on the side of the bracket *c'*; and whose upper horizontally disposed end *m''* has a lateral extension *m'''* faced with leather or other suitable friction material. When the upper end *o* of this lever is rocked upwardly it engages the horizontal part *n'* of the angular rack *n* pivoted at *n''*. *o* is the usual pinion, engaged by the rack, turning with the toothed escape-
ment wheel *o'*.

Referring, for instance, to Fig. 2, the vertically disposed stop lever *g* pivoted on the frame stands is held by a spring *g''* in normal position in which it will engage the margin stops *e'* and arrest the carriage. To release the carriage for printing an additional letter or letters at the right hand margin, the upper end of the lever *g* may be rocked rearwardly out of the path of the margin block by action of end *i* of arm *i'* when the latter is rocked rearwardly. For tabulator work, a greater extent of movement rearwardly of the upper end of lever *g* will carry it into the paths of the tabular stops *f''* before which, however, the rack bar is lifted, against the tension of its springs *n''*, from engagement with the pinion *o* by action of the part *i''* of the arm *i'* upon the lower end *m* of the rack release lever. The different lengths of movement for co-operative action of the stop lever *g* and margin stop *e'*, and of said lever with the rack release lever and tabular stops *f''*, is afforded by moving the arm *i'* on the rock shaft *k* through arcs of different length. In Figs. 1 and 2 this is accomplished by key levers having vertically movable finger pieces in the key board and arranged respectively adjacent opposite sides of the machine.

The key lever *p* arranged adjacent the left hand side of the machine is designed for operating the vertically disposed stop lever *g* in conjunction with the tabular stops and is adapted therefore to give that lever its greatest range of rearward movement. The key lever rocks about an axis *p'* being sustained in normal position by any suitable spring such as *p''*. An extension *p''* of the lever above its axis extends over the rock shaft *k* and has in it a laterally projecting pin or stud *p''* that normally lies against the rear face of a radial projection *k'* rigidly secured to the rock shaft. When the key lever is depressed, it acts through its entire range of depression

upon the projection k' , rocking the shaft k to such extent as not only to effect, as described, release of the rack, but also to carry the lever g into the paths of the tabular stops. At the opposite or right hand side of the machine, Fig. 2, is a similar key lever q turning also about the axis p' which may be a rod extending transversely of the machine between its side plate. An upward extension 10 q' of the lever extends over the rock shaft k and has a lateral pin q^2 that acts upon a radial projection k^2 on the rock shaft but is normally separated therefrom by a suitable interval as seen in Fig. 2. On depression of 15 this key, no movement of the rock shaft occurs until the pin q^2 comes in contact with the arm k^2 when, as described, a sufficient forward movement is imparted to the arm i' to carry the lever g rearwardly out of the path 20 of the margin stop, but not sufficiently great to release the rack from the pinion o nor cause the lever to engage the tabular stops.

A modification illustrated in Fig. 5 consists in providing at the front of the machine 25 a horizontally disposed push pin r equipped with an ordinary finger piece r' and jointed at its rear end to a lever s pivoted at s' and having applied to it, above its pivot, a spring s^2 , the reaction of which tends to 30 throw the upper end of the lever forward and maintains the push pin in normal projected position. The lower end of the lever is equipped with a roller t that bears upon the upper edge of the key lever p . Instead, 35 therefore, of depressing the key lever by means of its finger piece, it may be depressed and the described operations accomplished by pushing the stem r inwardly. With this arrangement, if desired, the lever (for instance p) need not have a finger piece in the key board, but may be cut off, if desired, at a suitable point such as that, for instance, indicated by the dotted line x . The primary purpose of this arrangement, however, is to 45 dispense with the key lever q . By employment of the devices s , r , the lever p may be depressed only sufficiently for to cause stop g to disengage the margin stop, and by complete depression of p by means of its finger 50 piece in the keyboard the lever m may be moved to such extent as to disengage the rack and move the stop lever g to such position as to engage the tabular stops.

The arrangement of tabular stops f' and 55 margin stops e' on the carriage and co-operating stop g on the frame are claimed in my application Serial No. 244,022, filed February 3, 1905. This application is based upon subject matter not disclosed in the said application No. 244,022.

I claim:

1. In a writing machine, the combination with the carriage having a margin stop and tabular stops arranged in line parallel with the axis of the platen, a co-operating stop 60

lever pivoted upon the frame and movable transversely to the platen axis, a rock shaft arranged transversely of the machine, an arm extending therefrom and adapted to engage the end of the stop lever, two pivoted levers and operative connections between them and the rock shaft whereby the respective levers may, when operated, impart different ranges of movement respectively to the rock shaft for the purpose set forth. 75

2. In a writing machine, the combination of a carriage provided with a margin stop and tabular stops arranged in different transverse lines, a co-operating stop lever pivoted on the frame of the machine and disposed between the two lines in which said carriage stops are mounted, a rack release lever, a rock shaft, an extension from the rock shaft adapted to engage the stop lever and rack release lever, two rock shaft operating levers and operative connections between the latter and the rock shaft whereby the respective levers may, when operated, impart different ranges of movement to the rock shaft, one to carry the stop lever out of the path of the margin stop and the other to operate the rack release lever and carry the stop lever into the paths of the tabular stops. 80

3. In a writing machine, the combination with the carriage having a margin stop and tabular stops arranged in line parallel with the axis of the platen, a co-operating stop lever pivoted upon the frame and movable transversely to the platen axis, a rock shaft arranged transversely of the machine, an arm extending therefrom and adapted to engage the end of the stop lever, and means whereby the operator may at will impart different ranges of movement to the rock shaft for the purpose set forth. 95

4. In a writing machine, the combination of a carriage provided with a margin stop and tabular stops arranged in different transverse lines, a co-operating stop lever pivoted on the frame of the machine and disposed between the two lines in which said carriage stops are mounted, a rack release lever, a rock shaft, an extension from the rock shaft adapted to engage the stop lever and rack release lever, and means whereby the operator may at will impart different ranges of movement to the rock shaft, one to carry the stop lever out of the path of the margin stop and the other to operate the rack release lever and carry the stop lever into the paths of the tabular stops. 100

5. In a writing machine, the combination of the carriage having a margin stop and tabular stops arranged in line parallel with the axis of the platen, a co-operating stop lever pivoted upon the frame of the machine with its upper end disposed between said two lines, a rock shaft arranged transversely of the machine and having a projecting arm adapted to engage the lower end of said stop lever, a 115

lever operating upon the rock shaft, a horizontally disposed push pin mounted at the front of the machine and an operative connection between it and said lever whereby when the push pin is operated the lever is actuated.

6. In a writing machine, the combination of the carriage having a margin stop and tabular stops arranged in different transverse lines, a stop lever pivoted upon the frame of the machine with its upper end disposed between said two lines, a rock shaft arranged transversely of the machine and having a projecting arm adapted to engage the lower end 15 of said stop lever, a lever operating upon the rock shaft and having a finger piece in the key board, a horizontally disposed push pin mounted at the front of the machine and an operative connection between it and said lever whereby when the push pin is operated the lever is actuated.

7. Tabular stops and a margin stop, combined with a co-operating stop, means comprising a lever for moving the co-operating 25 stop different distances according to the extent of movement of said lever, and means whereby the operator may at will move the lever to disengage the co-operating stop from the margin stop, and give the lever a greater movement to cause the co-operating 30 stop to engage a tabular stop.

8. Tabular stops and a margin stop carried by the carriage, combined with a co-operating stop mounted in the frame, means comprising a lever for moving the co-operating 35 stop different distances according to the extent of movement of said lever, and means

whereby the operator may at will move the lever to disengage the co-operating stop from the margin stop, and give the lever a greater 40 movement to cause the co-operating stop to engage a tabular stop.

9. Tabular stops and a margin stop combined with a co-operating stop, a horizontally disposed lever extending toward the front of the machine and operatively connected with the co-operating stop whereby the latter stop may be moved different distances according to the movement of said lever, means for moving the lever one distance 45 to disengage the co-operating stop from the margin stop and means for moving it a further distance to engage the co-operating stop with a tabular stop.

10. Tabular stops and a margin stop combined with a co-operating stop and a lever operatively connected with the co-operating stop to impart to it different ranges of movement according to the extent of movement of said lever, for the purpose set forth. 55

11. Tabular stops and a margin stop combined with a co-operating stop and a lever operatively connected with the co-operating stop to impart to it different ranges of movement to either merely disengage the co-operating stop from the margin stop or to move it to engage a tabular stop. 65

In testimony whereof, I have hereunto subscribed my name.
